US0D1042806S

(12) **United States Design Patent** (10) **Patent No.:** **US D1,042,806 S**
(45) **Date of Patent:** **** Sep. 17, 2024**

(54) **INJECTION DEVICE**

(71) Applicant: **HALOZYME, INC.**, San Diego, CA (US)

(72) Inventors: **Todd J. Leadens, II**, Maple Grove, MN (US); **Baylor Frantz**, Minnetonka, MN (US); **Scott Beacher**, St. Louis Park, MN (US); **Kevin Swanson**, Plymouth, MN (US); **Mike Travanty**, Wayzata, MN (US)

(73) Assignee: **HALOZYME, INC.**, San Diego, CA (US)

(**) Term: **15 Years**

(21) Appl. No.: **29/869,164**

(22) Filed: **Dec. 22, 2022**

(51) **LOC (14) Cl.** **24-02**

(52) **U.S. Cl.**

USPC **D24/114**

(57) **CLAIM**

The ornamental design for an injection device, as shown and described.

DESCRIPTION

FIG. 1 is a front perspective view of an injection device showing our new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines depict portions of the injection device that form no part of the claimed design.

1 Claim, 7 Drawing Sheets
